[57] CLAIM

The ornamental design for a tray structure or the like

for use in conjunction with a laboratory rack, as shown and described.

DESCRIPTION

FIG. 1 is a top view of a tray structure or the like for use in conjunction with a laboratory rack embodying my new design.

FIG. 2 is a front view taken along line 2—2 of FIG. 1.

FIG. 3 is a side view taken along line 3—3 of FIG. 1.

FIG. 4 is a back view taken along line 4—4 of FIG. 1.

FIG. 5 is a fragmented front sectional view, taken along line 5—5 of FIG. 1, with wall thickness exaggerated for clarity.

FIG. 6 is a fragmented side sectional view, taken along line 6—6 of FIG. 1, and with wall thickness also exaggerated for clarity.

A bottom view of the tray structure is the same as the top view of FIG. 1 but with projections shown as recesses and vice versa.

A flange portion, shown as an extreme peripheral edge in FIG. 1, and illustrated as a wall thickness, by a pair of narrow parallel horizontal lowermost lines in FIGS. 2—4, are exaggerated in thickness so that the flange portion could be more clearly illustrated.
